Attorneys

UNITED STATES PATENT OFFICE.

WALTER WILLIAM CARLSON, OF MANHATTAN, KANSAS.

CLOTHES WRINGER.

Application filed July 9, 1921. Serial No. 463,479.

To all whom it may concern:

Be it known that I, WALTER W. CARLSON, a citizen of the United States, and a resident of Manhattan, in the county of Riley and State of Kansas, have invented certain new and useful Improvements in Clothes Wringers; and I do hereby declare the following to be a full, clear, and exact description of the invention, such as will enable others skilled in the art to which it appertains to make and use the same.

This invention relates to improvements in clothes wringers, particularly to such as are adapted to be driven by a motor and in which one of the roller shafts may be utilized also to operate devices in addition to the wringer,—one object of the invention being to provide simple and efficient safety devices for a clothes wringer and to so locate the manually operable member of said safety devices that the natural tendency of a user whose hand may have been caught between the rolls, will be to move his hand upwardly in an effort to release the same and thus cause the safety devices to be at once operated and one of the rolls to be separated from the other and cease to rotate.

With this and other objects in view, the invention consists in certain novel features of construction and combinations of parts as hereinafter set forth and pointed out in the claims.

In the accompanying drawings, Figure 1 is a front elevation of a wringer embodying my improvements. Figure 2 is a rear view. Figure 3 is a plan view, and Figures 4 and 5 are sectional views.

The frame of the device is indicated at 1 and is located near a tub 1^a and a frame 1^b may be located on the latter. The wringer frame 1 is rigidly secured at one end to a tubular standard 2 and the latter passes freely through a plate 3 rigid with the tub frame 1^b, in which it may turn. The lower end of the tubular standard may be mounted to turn in a part on a gear case located at or near the bottom of the tub. The plate 3 is provided with notches 4—5 to be engaged by a latch 6 pivotally attached to the frame 1 whereby the device may be held in proper position relatively to a tub or held in position and prevented from swinging when shifted away from the tub. The latch 6 will be held in engagement with the notched plate by means of a spring 7 encircling a

rod 8,—the latter being attached to the latch and passing through a lug 9 on the frame. The rod 8 is extended to the other end of the frame and passes through a lug 11 on the latter,—the free end of said rod being provided with a finger-hold 12 to facilitate its manual operation. The frame 1 is provided with standards 13 suitably spaced apart and provided with bearings in which the shaft 14 of the lower rubber covered roller 15 is mounted. Arms 16 project forwardly from the standards 13 and are provided with bearings for the journals of a comparatively small wooden roller 17, the latter being disposed in front of and in proximity to the lower roller 15. To the forward ends of the arms 16, arms 18 are pivotally connected and at the free ends of the latter enlargements 19 are provided and these enlargements are made tubular in form to constitute bearings 75 for the shaft 20 of the upper rubber covered roller 21 of the wringer. The shaft 20 is provided at one end with a suitable pinion 22 which receives motion from a pinion 23 secured to the shaft of the lower roller. The shaft 14 of the lower roller is coupled to a shaft section 24 which in effect constitutes a continuation of said shaft 14 and the shaft section or continuation 24 of the lower roller shaft 14 is mounted in suitable 80 bearings 25 at the upper ends of arms 26 rigid with and projecting upwardly from the frame 1. Beveled gears 27—28 are secured to the shaft extension 24 and suitably spaced apart and one or the other of these beveled gears receives motion from a beveled pinion 29. The beveled pinion 29 is secured to the upper end of a driving shaft 30 depending into the tubular standard or upright 2, with which driving means from a suitable motor or source of power may be connected. The beveled pinion and its driving shaft are supported by an arm 31 pivotally mounted on the frame 1 and this arm is provided at or near its free end with a groove 32 which receives a crank 33 at the lower end of a manually operable shaft 34 mounted in the casting 35 which encloses the gearing. The manually operated shaft 34 is provided at its upper end with a crank handle 36 for operating it to shift the beveled pinion from one of the gears to the other to control the direction of rotation of the wringer rolls.

The standards 13 are provided at their upper ends with rearwardly projecting arms 110

37 having elongated slots 38 through which rods 39 pass, said rods being provided at their lower ends with nuts 40 to constitute bearings for the lower ends of tension springs 41 mounted on said arms,—the upper ends of said tension springs being adapted to bear (when the rods 39 are moved upwardly) against the slotted arms 37 at the upper ends of the standards 13. The upper ends of the 10 rods 39 are pivotally connected in bifurcated portions of levers 42 and the free ends of the latter are connected by a tripping-bar 43,—said levers and tripping-bar thus forming a yoke. The bifurcated ends of the two 15 levers of the tripping yoke are provided with lugs 44 adapted to engage lugs 45 on the enlargements 19 of the arms 18 which carry the upper roll. From this construction and arrangement of parts, it is evident 20 that when the tripping-yoke is moved forwardly, the springs 41 will be compressed and the upper roll will be pressed, under the tension of said springs, upon the lower roller, and in order to limit the forward and 25 downward movement of the tripping-yoke, the levers thereof may be provided with lugs 42^a to engage the arms 18. When the tripping-yoke is moved forwardly and downwardly as above explained, the upper 30 portions of the rods 39 will enter between the lugs 45 carried by the arms 18 and the pivotal connections of said rods with the levers 42 will pass a dead center extending through said pivotal connections and the 35 mountings of said levers on the lugs 45 of the arms 18 and thus the tripping devices will be held in the positions they assume when the wringer is in operation.

Should the operator's hands become 40 caught between the rolls, the natural tendency will be for him to jerk them upwardly and in so doing he will strike the tripping bar and thus raise the tripping-yoke, causing the pivotal connections to move backwardly past the dead centers and the 45 tension of the springs removed,—leaving the arms 18 and the upper roller carried thereby free to rise and the pinion on the shaft of the upper roll to move out of mesh with the 50 pinion which drives it, thereby stopping the rotation of said upper roll.

An inclined apron 46 for directing water wrung from the clothes, back into the tub is suitably mounted on the frame 1 and 55 guard arms 47 may extend upwardly from re-

spective ends of the apron at respective ends of the wringer rolls.

The shaft extension of the lower wringer roll 15 may be utilized for operating another device, such as an ice cream freezer, coffee mill or meat grinder. In the drawing I have shown an ice cream freezer 48 to be mounted on a bracket 49 (Fig. 5) supported by the wringer tube or standard 2 and having its operating shaft coupled to the shaft 65 extension 24 of the lower wringer roll, as indicated at 49.

Having fully described my invention what I claim as new and desire to secure by Letters-Patent, is:

1. The combination with the frame of a clothes wringer and a lower wringer roll mounted therein, of arms pivoted to said frame and having journal bearings near their free ends, an upper wringer roll having its journals mounted in said bearings, lugs projecting from said bearings, a tripping-yoke having lugs to engage the upper side of said first mentioned lugs, said yoke including a member normally disposed approximately in front of the rolls, rods connected with said yoke near the lugs thereon, springs on said rods, abutments for the lower ends of said springs on said rods, and abutments on the frame for the upper ends 85 of said springs.

2. The combination with the frame of a clothes wringer and a lower roll journalled in said frame, of arms pivoted to said frame, an upper roll journalled in said arms near 90 the free ends of the latter, two lugs at the free end of each of said arms, tripping levers having bifurcated portions provided with lugs to engage the upper side of the lugs on said arms, rods pivoted in the bifurcated portions of said levers and movable between the lugs on the arms, slotted arms on the frame through which said rods pass, springs on said rods bearing at their upper ends against said slotted arms, abutments on 95 said rods for the lower ends of said springs, and an operating bar connecting said tripping levers.

In testimony whereof I have signed this specification in the presence of two sub- 100 scribing witnesses.

WALTER WILLIAM CARLSON.
